UNITED STATES PATENT OFFICE.

JOHN W. FARLEY, OF CLEVELAND, OHIO.

PLATE THIMBLE FOR PIPES.

Application filed October 24, 1927. Serial No. 238,329.

The invention relates to plate assemblies, commonly known as plate thimbles, devices of this character being employed to extend around pipes and cover floor or wall openings, provision being made whereby the pipes may move under expansion and contraction without injury to the plate thimbles. Heretofore, the construction of plate thimbles has necessitated a sectional formation for at least the outer plate, permitting proper engagement of guides carried by said plate with edges of an inner relatively small plate. With such constructions, it has been necessary to make more or less expensive provision for connecting the sections of the outer plate. It is an object of my invention however, to provide a new and improved construction in which both the outer relatively large plate and the inner comparatively small plate, may each be of one-piece formation. In carrying out this end, a further aim is to provide a novel process of constructing a plate thimble, enabling the inner comparatively small plate to be properly engaged with the guides carried by the outer plate, after securing of said guides to said outer plate.

With the foregoing in view, the invention resides in the novel subject matter herein-after described and claimed, the description being supplemented by the accompanying drawing.

Fig. 1 is an outer side elevation of a plate thimble constructed in accordance with my invention.

Fig. 2 is an inner side elevation.

Fig. 3 is a vertical sectional view on line 3-3 of Fig. 1.

Fig. 4 is a longitudinal sectional view showing the manner of initially assembling the two plates.

Fig. 5 is a view similar to Fig. 2 but showing a modified form of construction.

Fig. 6 is a view similar to Fig. 2 but illustrating a dual form of construction.

The form of the invention shown in Figs. 1, 2, 3 and 4 will first be described. In these views, 7 denotes a flat sheet metal plate formed with a slot 8 and having its edges bent laterally to provide side and end flanges 9-10 respectively, said flanges all projecting in the same direction and serving as means for spacing the body portion of the plate 7 from a floor, wall, etc. The corners of the plate are formed with openings 11 to receive suitable attaching fasteners such as screws 12.

Two metal strips 13 are secured against the inner side of the plate 7 by spot welding or other desired fastening means 14, the inner edges of these plates being disposed at the side edges of the slot 8 and being inwardly offset to provide guides 15 for an inner relatively small plate 16, said plate having a pipe-receiving opening 17 for registration with said slot 8.

In constructing the device, the plate 7 with its flanges 9-10 and the guides 15, is constructed as one unit and the plate 16 constitutes a separate unit. Then to assemble these two units, plate 16 is longitudinally sprung and while so sprung, is slid across the free edge of one of the flanges 10, into engagement with the guides 15, and as soon as plate 16 passes said flange, its own resiliency causes it to snap inwardly within the confines of the flanges 9-10, the flanges 10 then serving to hold the plate against sufficient sliding movement to become accidentally disengaged from the guides, before installation of the device.

Fig. 5 discloses a construction analogous to that above described, but the guides 15^a for the inner plate 16^a, are in the form of transverse strips having their ends spot welded or otherwise secured at 14^a to the outer plate 7^a.

In Fig. 6, a dual construction is shown, in which the outer plate 7^b is formed with a plurality of slots 8^b, an equal plurality of inner plates 16^b being provided for closing these slots. Guides may be provided for these plates 16^b, of the type shown in Fig. 2 or the form shown in Fig. 5, the guides 15^b being identical with the guides illustrated in Fig. 2.

In all instances, the guides for the inner plate are so spaced from the end flanges of the outer plate, as to permit assembly of the inner and outer plates by longitudinally springing and sliding the inner plate or plates as above described.

It will be seen from the foregoing that the invention is of extreme simplicity and hence may be manufactured and sold at small cost. However, it will be equally as efficient as more expensive constructions heretofore produced.

I claim:

1. A device of the class described comprising a one-piece relatively large outer plate formed with a slot and having its edges turned laterally in the same direction to provide side and end flanges, a one-piece

relatively small inner resilient plate contacting slidably with the inner side of said outer plate within the confines of said flanges, said inner plate having an opening 5 for registration with said slot, and guides for slidably mounting said inner plate, said guides being secured to said outer plate and lying against the inner side of said inner plate.

10 2. A structure as specified in claim 1; said guides being spaced from said flanges and disposed in such spaced relation with one of said flanges as to permit sliding of said inner plate across the free edge of said 15 one flange and into engagement with said guides upon longitudinal springing of said inner plate, the resiliency of the inner plate serving to snap it inwardly past said one flange to a position within the confines of 20 said flanges, when moved inwardly to a sufficient extent.

3. A device of the class described comprising a one-piece relatively large outer plate stamped from sheet metal and having 25 a rectangular form, the central portion of

said plate being formed with a slot which extends longitudinally of said plate, the end and longitudinal edges of said plate being laterally stamped to provide a continuous peripheral flange to contact with a support 30 and space the body portion of the plate from said support, the corners of the plate being formed with openings to receive attaching fasteners; a relatively small, one-piece, resilient sheet metal plate lying against the 35 central longitudinal portion of said outer plate and disposed at the inner side of the latter, said inner plate covering said slot and being formed with a pipe-receiving opening registering therewith, and stamped 40 metal guide plates welded to the inner side of said outer plate between the side flanges of the latter and said inner plate, the inner edges of said guide plates being offset and slidably receiving the longitudinal edges of 45 said inner plate.

In testimony whereof I have hereunto affixed my signature.

JOHN W. FARLEY.
